United States Patent Office

Des. 229,566
Patented Dec. 11, 1973

229,566

LOUDSPEAKER CABINET

Paul W. Klipsch, Hope, Ark., assignor to Klipsch and
Associates, Inc., Hope, Ark.

Filed Oct. 12, 1971, Ser. No. 188,660

Term of patent 14 years

Int. Cl. D14—01, 03

U.S. Cl. D26—14 G

FIG. 1 is a perspective view showing the front, top and one side of a loudspeaker cabinet incorporating my new design;

FIG. 2 is a perspective view showing the rear, a side and a top thereof;

FIG. 3 is a bottom plan view thereof.

I claim:

The ornamental design for a loudspeaker cabinet, as shown.
